Oscar Joseph Walinsky
Inventor
By his Attorney
Terryon & Terryon

UNITED STATES PATENT OFFICE.

OSSIP JOSEPH WALINSKY, OF SEA GATE, NEW YORK, ASSIGNOR TO WHITE LUGGAGE CO. INC., OF NEW YORK, N. Y., A CORPORATION OF NEW YORK.

HATBOX.

Application filed April 22, 1926. Serial No. 103,754.

This invention relates to luggage and more especially to hatboxes.

An object of this invention is an improved hatbox having a hinged tray which forms a separate compartment within the box for the hat and which also serves as a carrier for toilet articles and the like.

According to the invention, the hatbox comprises a main portion to which is hinged a cover having a flange which fits around a rim projecting from the edge of the body of the box. A tray of proper size to fit snugly within the box is hinged to the upper edge of the box by means of a flexible hinge piece, and means are provided to support the tray within the body of the box to form a separate compartment, so that the cover may be opened without exposing the hat. Because of the flexible hinge piece, the tray may be arranged within the cover of the box if desired, and means are provided for retaining it in this position when it is desired to have access to the body of the box. Pockets may be provided on either side of the tray for carrying toilet articles and the like.

Other objects, novel features and advantages of the invention will be apparent from the following specification and accompanying drawings, wherein—

Figure 1 is a perspective view, partially broken away, of a hatbox equipped with a tray in accordance with the invention; and Fig. 2 is a detail perspective view partially in section illustrating the means for supporting the tray within the box.

The hatbox comprises a body or main receptacle 10 which may be of any suitable configuration but is usually substantially circular in cross-section with a flattened portion upon which the box may rest. From the upper edge of the box extends a rim 11 of slightly less exterior diameter than the box. A cover 12 has a flange 13, the edge of which is connected to the upper edge of the body 10 by the usual metal hinge (not shown). The flange 13, when the box is closed, fits around the rim 11 and rests upon the upper edge of the body 10. At the bottom of the box is provided the usual hat form 14. The interior of the body portion and also the interior of the cover may be lined in the usual manner, and a pocket 15 may be provided in the body portion and a

pocket 16 in the cover. Straps 17 limit the extent of opening of the cover.

A tray 18 is provided of suitable size to fit easily within the body 10. This tray is hingedly mounted by means of a flexible hinge strip 19 which is attached, as by stitching or otherwise to the rim 11 near its upper edge. The tray 18 may be supported within the body in any suitable manner but is preferably supported by means of a collar 20 provided within the body portion. This collar is arranged between the lining of the body portion and the material composing the body portion, and the lining is sufficiently loose so that when the tray is lowered against the collar, it will fold to conform to the collar. On the under face of the tray is provided a tab 21 which folds over the edge of the tray and extends slightly thereabove, so that it may be grasped when it is desired to lift the tray. Because of the provision of the hinge strap 19 and the attachment thereof to the upper edge of the rim 11, the tray may be swung up into the cover 12, when it is desired to have access to the body of the box. The tray may be held within the cover by means of a tab 22 having a snap fastener which co-operates with a fastener 23 which also serves to attach the tab 21 to the tray 18. When the tray is arranged within the cover, the tab 21 underlies the tray and the tab 22 passes over the edge of the tray and the tray is held in position by engagement of the snap fastener on the tab 22 with the fastener 23.

The tray 18 may be lined with the same material with which the body and cover are lined, and there may be provided on either side of it pockets within which toilet articles or the like may be carried. When the tray is arranged within the body portion, the cover may be raised without exposing the contents of the body of the box; and when it is desired to have access to the body of the box, the tray may be swung up into the cover out of the way. The tray takes up but a small amount of space, but is most convenient, both because of its function of protecting the contents of the body portion when the cover is open, and also because of its pockets which provide a convenient way of carrying small articles.

While the construction above illustrated

and described is regarded as the preferred embodiment of the invention, it is, of course, understood that the invention comprehends all such changes and modifications as may 5 fall within the scope of the appended claim.

What I claim and desire to secure by United States Letters Patent is:

A hat box comprising a body, a cover hinged to said body at a point removed from 10 the edge thereof, a tray, a flexible hinge piece

attached to said tray and to the upper edge of said body whereby said tray may be arranged either within said body or said cover, means to support said tray within said body to act as a cover therefor and means to maintain said tray in said cover when not so used.

In testimony whereof, I have signed my name to this specification.

OSSIP JOSEPH WALINSKY.
